United States Patent Office

Des. 183,028
Patented June 10, 1958

183,028

CIGARETTE MERCHANDISING MACHINE

Raymond Spilman, Darien, Conn., and Walter L. Koch, Staten Island, N. Y., assignors to Rowe Manufacturing Co., Inc., Whippany, N. J., a corporation of New York

Application October 17, 1957, Serial No. 48,146

Term of patent 14 years

(Cl. D52—3)

The figure is a perspective view of a cigarette merchandising machine showing our new design. The back and side not shown in the drawing are plain.

We claim:

The ornamental design for a cigarette merchandising machine, substantially as shown and described.
